UNITED STATES PATENT OFFICE.

ARTHUR ALBERT CHURCHILL, OF PORTLAND, OREGON.

TRACK-SANDING DEVICE.

No. 856,765.

Specification of Letters Patent.

Patented June 11, 1907.

Application filed February 23, 1907. Serial No. 358,888.

To all whom it may concern:

Be it known that I, ARTHUR ALBERT CHURCHILL, a citizen of the United States, and a resident of Portland, in the county of 5 Multnomah and State of Oregon, have invented a new and Improved Track-Sanding Device, of which the following is a full, clear, and exact description.

This invention relates to certain improvements in track sanding devices, and more particularly to the specific means whereby the sand may be delivered from the sand box to the track by the force of compressed air supplied from the air brake system or other 15 suitable source.

The object of the invention is to provide means for controlling the delivery of the sand, so simple in construction and easily assembled, that it may be manufactured by an 20 ordinary mechanic and the use of all special castings and delicate mechanism obviated.

A further object of the invention is to provide means whereby the sand delivery pipe may be readily freed from all obstructions 25 should it become clogged, and whereby the cleaning thereof may be accomplished without necessitating the removal of any of the sand from the sand box.

Reference is to be had to the accompanying drawings forming a part of this specification, in which similar characters of reference indicate corresponding parts in both the figures, and in which

Figure 1 is a side elevation of a portion of a 35 car provided with my improved sanding device; and Fig. 2 is a vertical section through the operating mechanism thereof.

To more clearly disclose the construction and operation of my improved device, I have 40 illustrated a portion of a car having a car floor 10, and a car body 11 supported upon a suitable truck 12, within which are mounted the wheels 13. These latter travel upon a track 14, and my improved sanding device is 45 so constructed as to deliver the sand upon the track closely adjacent and in front of the wheels 13. As shown, the car is provided with a sand box 15, and within this sand box is located my improved device for delivering 50 the sand. The car is preferably provided with an air brake system, and connected to this system is an air pipe 16 having a branch 55 17 entering the sand box through the car floor and bottom of the sand box. Within the bend in the pipe 16 and preferably within the reach of the motormen or car driver, I

provide a suitable controlling valve 18, whereby the supply of air to the sanding device may be readily controlled.

Extending through the bottom of the sand box and through the car floor, I provide a short conduit 19 connected to an ordinary T-joint 20 within the sand box, the lower end of said T-joint fitting within a recess 21 in the bottom of the box. Below the car floor 60 I provide a suitable washer 22 in engagement with the bottom of the car floor, and connected to the end of the conduit 21 I provide a sleeve 23 serving to hold the washer 22 in firm engagement with the bottom of the car 70 and to also serve as means whereby the curved delivery pipe 24 may be attached. The T-joint 20 is connected to an upright pipe 25 in alinement with the conduit 19 and extending to a point adjacent the top of the 75 sand box. The upper end of this pipe is normally closed by a cap 26, readily removable. The T-joint 20 is connected to a short pipe 27 lying closely adjacent the bottom of the sand box and at right angles to the conduits 80 19 and 25. The outer end of the conduit 27 is connected to a coupling 28 having a V-shaped opening cut in its upper side and having an air delivery nozzle 30 extending into the open end of the coupling and terminating 85 adjacent the lower end of the V-shaped opening. The nozzle is supported by any suitable clamping means 31 and is connected by a suitable pipe bend 32 to the air delivery pipe 17 previously referred to. 90

When it is desired to deliver air to the track, the valve 18 is opened and a blast of air is delivered through the nozzle 30 and past the V-shaped opening, whereby sand is forced through the conduit 27 and permitted 95 to escape through the delivery pipe 24. In case this pipe should become clogged the cap 26 may be readily removed and a wire or other suitable means may be inserted through the upper end of the pipe 25 to remove or 100 loosen the obstructions.

The relative position of the nozzle and the opening in the coupling 28 insures a supply of sand in front of the nozzle 30 at all times, and by providing the recess 21 in the bottom of 105 the sand box, I bring the conduit 25 and coupling 28 as nearly as possible to the bottom of the box, whereby a larger portion of the sand may be permitted to escape. The sleeve 23 serves a double function of rigidly 110 securing the entire sanding device in place, and also serving as means whereby the de-

livery conduit 24 may be readily secured and, if desired, quickly detached.

Having thus described my invention, I claim as new and desire to secure by Letters Patent:

1. A track sanding device, comprising a sand box, a conduit extending through the bottom of the box and terminating at a point adjacent the top thereof, means for normally closing the upper end of said pipe; a branch conduit entering the first mentioned conduit adjacent the bottom of the box, said last mentioned conduit being provided with an opening in communication with the interior of the box, and means for forcing the contents of the box through the last mentioned conduit into the first mentioned one.

2. A track sanding device, comprising a sand box, a conduit terminating adjacent the top of the box and leading to a point adjacent the car wheel, a removable cap normally closing the upper end of said conduit, a branch conduit within said box and lying substantially parallel to the bottom thereof and hav-

ing one end in communication with the first mentioned conduit and having a V-shaped notch in its upper side, and an air pipe having a delivery nozzle terminating within the branch conduit and below said opening therein.

3. A track sanding device, comprising a sand box, a vertically disposed conduit extending through the bottom of the box and terminating adjacent the top thereof, a branch conduit entering the first mentioned conduit adjacent the bottom of the box, said last mentioned conduit having an open end and a V-shaped opening in its upper surface, and an air delivery nozzle extending within the open end and terminating below said opening.

In testimony whereof I have signed my name to this specification in the presence of two subscribing witnesses.

ARTHUR ALBERT CHURCHILL.
